PILE EXTRACTOR

Walter Behm, Rochester, Mich.

Application October 31, 1938, Serial No. 238,119

8 Claims. (Cl. 254—139)

This invention relates to pile extractors and particularly to extractors for interlocking metal piles.

An object of the invention is to install on a suitable mast a block and tackle mechanism for multiplying a force applied to extract piling, and to equip such mast with a seating member having a provision for engaging it firmly with one of a row of interlocked metal piles, while another of such piles is being extracted.

Another object is to provide the seating member of said mast with a pair of depending ribs conformed in shape to the offset mid portion of a standard type of pile and adapted to so straddle such pile that the latter will restrain the mast from horizontal shifting in any direction.

A further object is to adapt said seating member to be secured to the mast in either of two positions differing by one hundred and eighty degree rotation about the mast axis, to facilitate seating the mast on any of a row of piles which are offset in opposite directions on alternate piles.

A further object is to adapt said seating member to swivel about the vertical axis of the mast, and to provide means for latching it to the mast in either of two positions, differing by a hundred and eighty degree rotation, and to yieldably hold it in either latched position by spring means which may be manually overcome.

A further object is to equip the seating member with handle elements facilitating its rotative manipulation, and to derive a latching function from such elements.

These and various other objects are attained by the construction hereinafter described and illustrated in the accompanying drawings, wherein:

Fig. 1 is a side elevational view of the extractor, showing its working relation to a row of metal piles.

Fig. 2 is an elevational view of the same, as seen at right angles to Fig. 1.

Fig. 3 is a cross sectional view, taken on the line 3—3 of Fig. 1.

Fig. 4 is a bottom view of the mast, particularly showing its seating provision.

Fig. 5 is a fragmentary elevational view showing the anchorage of a guy cable to one of the piles.

Fig. 6 is a fragmentary elevational view of a mast having an alternative provision for rotatively attaching a seating member.

Fig. 7 is a vertical sectional view of the same taken on the line 7—7 of Fig. 6.

Fig. 8 is a horizontal sectional view of the same taken on the line 8—8 of Fig. 6.

In these views, the reference character 1 designates a row of ordinary metal piles having any desired interlocking provision, such as exemplified at 2. As is common, the upper end portion of each pile is formed, midway between the interlocking margins, with one or more apertures 3 to facilitate handling.

The improved extractor comprises a mast 4, preferably of H-beam construction, and to the bottom of such mast is welded or otherwise rigidly secured a base plate 5 of heavy sheet metal. Removably attached to such plate is a seating plate 6 also of heavy sheet metal and preferably corresponding in its main dimensions to the plate 5. Welded to and extending centrally across the plate 6, therebeneath, is a pair of depending parallel ribs 7, shaped and spaced to straddle the upper end of any of the piles 1, whereon the plate 6 may be seated. When thus seated, the base of the mast is held in a vertically centered relation to the seat-forming pile, since relative movement transverse to the pile is obviously prevented, and the conforming offsets of the pile and ribs prevent horizontal movement in the approximate plane of the pile. The spacing of the ribs 7 affords them a fairly free and easily established engagement with a pile.

Attachment of the plate 6 to the plate 5 may be effected by providing a pair of upstanding pins 8 on the former plate near its margins remote from the ribs, and inserting such pins through openings 9 in the plate 5, locking pins 10 being then engaged with the pins 8 above the plate 5. Preferably a pair of handle members 10a are welded or otherwise secured to opposite margins of the plate 6 to facilitate its manipulation.

To the upper end of the mast are welded bearing plates 11 for a set of sheaves 12, such plates so projecting laterally from the mast as to locate the shaft 13 journaling said sheaves at a distance from the axis of the mast approximately equal to the distance between the axes of the piles 1. Tackle 14 engaging the sheaves 12 suspends a block 15 equipped with sheaves 16 and the power-applying span 17 of such tackle extends upwardly to engage the boom (not shown) of a hoist or derrick, and to extend on such boom to the hoist drum.

Carried by the block 15, at its lower end, is a pin 18 pivotally mounting a pair of depending, elongated pulling plates 19 jointly carrying at their lower ends a pair of pins 20 spaced for engagement in the openings 3 of any pile 1. The

pins 20 are interconnected by relatively long locking pins 21 inserted in openings transversely formed in the ends of the first-mentioned pins, whereby the latter are detachably held in the plates 19.

At the top of the mast, both flanges of the H-beam are preferably cut away, exposing the web of such beam, as an upstanding tongue 22. This is engaged by a guy cable 23 extending diagonally downward and anchored as shown at 24 in Fig. 5 10 to one of the piles 1, thus counteracting the lateral strain on the mast exerted by stresses in the tackle 14 when a pile is being extracted. An aperture 25 in the tongue 22 is engageable by a cable 25a for hoisting the mast to and from its 15 position of use, and holding it upright, during use.

In the modified type of mast shown in Figs. 6, 7, and 8, a seating plate 26 centrally carries an upstanding pin 27 which engages freely in a central aperture of the base plate 5'. To further accommodate such pin, the web of the mast 4' is formed adjacent to the plate 5', with an opening 28. The upper end of the pin 27 is reduced and threaded to receive a nut 29, beneath which a washer 30 is clamped against the shoulder 25 formed by reducing the pin. Compressed between such washer and the plate 5' is a coiled spring 31 surrounding the pin 27 and tending to hold the seating plate firmly against the plate 5'. Projecting oppositely from the seating plate is a 30 pair of handle members 32, welded or otherwise rigidly secured at their inner ends to the top face of the seating plate. The plate 5' is formed with marginal notches 33 at opposite points thereof to accommodate the inner ends of the handle members, the seating plate being thus latched in either of its positions of use.

In use of the appliance for extracting a row of sheet metal piles, the mast is initially seated on the pile next adjacent the one to be first extracted, usually the end one of the row. Having engaged the pulley plates with the last-mentioned pile and anchored the guy cable, power is applied to the line 17, and the block and tackle so multiplies the force applied through said line, that little difficulty is ordinarily experienced in effecting the extraction. The mast is then shifted to the next adjoining pile and the operation is repeated.

Each time the mast is shifted from one pile to the next adjacent one, it is necessary to rotate the seating plate through one hundred and eighty degrees, because of the alternating arrangement of the piles, best seen in Fig. 3. In either described form of the invention, the desired rotation may be quickly and easily effected. To rotate the plate 6, the locking pins 10 are removed, thus permitting withdrawal of the dowels 8 from the openings 9. The seating plate being thus removed is reversed, end for end, and again secured in place by the dowels and locking pins. The modified seating plate 26 does not require separation from the mast, in rotating such plate, it being necessary merely to unlatch the plate by exerting a downthrust on the handles 32, thus overcoming the spring 31 and disengaging said handles from the notches 33. Thereupon the seating plate is rotated, and when the handle ends again register with said notches, 70 the spring effects relatching of the plate.

It has been found that the described appliance permits extraction of sheet piling at a much more rapid rate than apparatus in present day use, because of the ease with which the appliance can 75

be set in a proper fixed position for each operation.

Furthermore, the appliance permits use of less expensive extracting equipment, as compared with equipment now required. Present equipment further requires greater power than the described appliance, the latter being readily operable by a gas engine, whereas steam equipment has heretofore been necessary.

It is also an advantage of the described appliance that it prevents a pile or a group of piles adjoining the one directly receiving the pulling stress from being lifted by frictional adhesion. Such prevention follows necessarily from seating the mast on the pile next adjoining the one to be extracted. It is in most cases quite undesirable to pull more than one pile through frictional adhesion, since the adhering piles are thus subjected to abnormal stresses, tending to bend them out of proper shape, and separation of several piles, if extracted in unison, is quite difficult to accomplish.

The invention is presented as including all such modifications and changes as come within the scope of the following claims.

What I claim is:

1. In a pile extractor, a portable mast, a seating plate for the mast, means swiveling the plate on the mast to turn about the mast axis, affording the plate a limited play along said axis, means yieldably urging the plate upwardly against the mast, and a pair of handles for manipulating the plate, projecting from opposite margins thereof, the mast having openings receiving portions of said handles in either of two positions of the plate, differing by a one hundred and eighty degree rotation of the plate, to latch the plate against rotation in either of such positions, actuation of the plate to the lower limit of its play serving to withdraw the handles from said openings.

2. An extractor for pulling arched, channel or trough shaped alternately reversed metal piles, comprising a portable mast, a plate for seating the mast having a downwardly opening groove with bent or curved ends to fit the top of one of said piles, means for securing the plate to the mast in either of two positions differing by a rotation of substantially one hundred and eighty degrees about the axis of the mast, whereby in shifting the mast from one pile to the next pile said plate may be turned to conform to the reversal of said next pile, without turning the mast, and power multiplying pulling mechanism on the mast, attachable to the pile to be extracted.

3. A pile extractor as set forth in claim 2, said plate securing means comprising a pair of dowel pins upstanding from the plate substantially at opposite sides of its center, the base of the mast having sockets accommodating said pins in either of said positions of the plate.

4. An extractor for pulling arched, channel or trough shaped alternately reversed metal piles, comprising a portable mast, a plate for seating the mast having a downwardly opening groove with bent or curved ends to fit the top of one of said piles, means swiveling the plate on the base of the mast to turn about the approximate vertical axis of the mast and occupy either of two positions differing by a rotation of substantially one hundred and eighty degrees, whereby in shifting the mast from one pile to the next pile, the groove of said plate may be conformed to the reversal of said next pile, without turning the mast, means for latching the plate to the

mast in either of its said positions, and power multiplying pulling mechanism on the mast attachable to the pile to be extracted.

5. In a pile extractor as set forth in claim 4, spring means for yieldably holding the plate in either of its latched positions.

6. In a pile extractor as set forth in claim 4, said swiveling means comprising a pin carried by and upstanding from the plate substantially centrally thereof and socketed in the mast, a spring coiled about said pin and reacting between the pin and mast to yieldably hold the plate upwardly against the mast, the plate being releasable from said latching means by overcoming said spring.

7. A pile extractor as set forth in claim 4, said latching means comprising a handle laterally projecting from the plate, the base of the mast having recesses at opposite points thereof to al-

ternatively receive said handle, according as the plate is in one or the other of said positions, said swivel means affording the plate a limited play to and from the mast to engage the handle in or disengage it from either recess.

8. A pile extractor as set forth in claim 4, said swiveling means comprising a pin carried by and upstanding from said plate substantially centrally thereof and socketed in the mast, a spring coiled about said pin and reacting between the pin and mast to yieldably hold the plate upwardly against the mast, the plate being releasable from said latching means by overcoming said spring, the mast having a web extending lengthwise thereof and substantially diametrical to the axis of the mast and such web having an opening adjacent to the seating plate accommodating said pin and spring.
